UNITED STATES PATENT OFFICE.

JOSEPH GORINAC, OF COLLINWOOD, OHIO.

RAILROAD-CROSSING.

1,322,238.

Specification of Letters Patent. Patented Nov. 18, 1919.

Application filed May 28, 1919. Serial No. 300,315.

To all whom it may concern:

Be it known that I, JOSEPH GORINAC, a citizen of Jugo-Slavia, residing at Collinwood, in the county of Cuyahoga and State 5 of Ohio, have invented certain new and useful Improvements in Railroad-Crossings, of which the following is a specification.

The primary object of the present invention is to provide an improved form of railroad crossing in which the rails at the crossing embody four relatively short portions positioned in the usual rectangular formation and so retained by interconnected cross brace bars extending therebetween.

15 A further object of the invention is to provide an improved form of cross plate for railroad crossings wherein the meeting ends of the rails are securely held in position upon the cross plates by an improved 20 form of fastening member.

With the above and other objects in view, the invention consists in the novel form, combination and arrangement of parts hereinafter more fully described and shown in 25 the accompanying drawings, in which like reference characters indicate similar parts throughout the several views.

In the drawings,

Figure 1 is a top plan view of a railway 30 crossing constructed in accordance with the present invention, and showing the interlocked crossed braces for the short sections of the rails,

Fig. 2 is an edge elevational view of the 35 form of the construction shown in Fig. 1,

Fig. 3 is a cross sectional view on line III—III of Fig. 1 taken through one of the cross braces,

Fig. 4 is a cross sectional view taken on 40 line IV—IV of Fig. 1, through one of the crossing plates,

Fig. 5 is an enlarged detached perspective view of one of the crossing plates,

Fig. 6 is a fragmentary perspective view 45 of one end of one of the cross braces,

Fig. 7 is a perspective view of one of the wedge blocks associated with the rail and chair plate,

Fig. 8 is a perspective view of a wedge 50 block associated with the cross braces, and

Fig. 9 is a perspective view of one end of the rail supported on the cross plate showing the flange carried thereby for guiding the wheel flange.

55 Referring more in detail to the accom-

panying drawing and particularly to Figs. 1 and 5, there is provided a crossing plate 10 having crossed rail seats 11 formed thereon by means of integral upstanding rail engaging fish bars 12 having the usual overhanging rail engaging portions 13, certain ones of which are provided with openings 14 therein adapted for the reception of lock bolts. The intersecting portion of the seats 11 is provided with an upstanding block 60 15 slightly projecting above the integral members 12 as illustrated in Fig. 5 and provided with cross grooves 16 extending in alignment with the seats 11 to permit passage of the flange of a car wheel.

As shown in Figs. 1 and 9, the rails 17 have the ends thereof slidably received in the seats 11 upon the plate 10 with the fish bars and flanges 12 and 13 engaging adjacent parts thereof while the tread 18 of the rail is provided with an integral flange 19 with the outwardly positioned end thereof flared as at 20 to insure the flange of the wheel properly entering the cross over and to guide the flange through the grooves 16 in 80 the block 15, it being noted that the flanges 20 are formed upon the adjacent sides of opposite rails as illustrated in Fig. 1.

In order to hold the rails positioned as illustrated, the blocks 21 shown in detail in Fig. 7 are positioned upon the base plate 10 between the rail 17 and one of the fish bars 12 that is apertured, while one end of the block is bifurcated as shown at 22 with an opening 23 through one leg thereof, said 85 opening adapted for registration with the adjacent opening 14 in the member 12 whereupon a locking bolt 24 is inserted with the retaining nut or other suitable keeper member 25 positioned upon the inwardly 90 projecting end thereof that terminates between the bifurcations as shown in Fig. 1 and when so positioned, the rails 17 are wedgingly held in engagement with the adjacent faces of the members 12 and the 100 block 15 with the groove formed by the guide flange 19 in alignment with the grooves 16 in the block 15.

Relatively short rail sections 26 extend between the crossing plates 10 and are 105 formed with flanges 27 which form a tension of the flanges 19 and grooves 16 so that in the cross over, there is provided a tread for the car wheel and a guide for the flange thereof. Similar blocks 21 are car- 110

ried by adjacent portions of the plates 10 and coöperate with the short rail sections 26 to secure the same in position.

To prevent the short rail sections from spreading or moving into closer relationship, and also to hold the cross over in its proper operative position, there are provided interengaging cross braces 28 substantially in the form of tie rods and connected at their intersecting portions as at 29, the ends thereof being provided with seats 30 for the short rail sections 26 with rail engaging flanges 31 at the terminal ends thereof while the inwardly positioned flange 32 is slightly spaced from the rail section 26 adapted for the reception of the block 33 provided with a recess 34 in the upper side thereof and with a bolt entering opening 35 in one wall that is adapted to register with an opening 36 provided in the end wall of the recess 37 in the top of the portion 32 and into which a locking bolt 38 is adapted to be received.

With this construction of cross over, the rails entering the plates 10 are held in their proper positions at all times by the permanent positioning of the plates caused by the cross braces 28 preventing any relative movement thereof while the short rail sections 26 are retained in their set position by said braces to insure the proper alining of the rails and grooves for the traction of the car wheels.

What I claim as new is:—

- 35 1. A railroad crossing comprising crossing plates, rail engaging bars carried thereby and defining crossed rail seats, an upstanding block at the intersection of the crossed seats and projecting slightly above said rail engaging bars with cross wheel flange grooves in the upper face thereof, rails having their ends received in said seats, flanges carried by the tread portions of said rails to define grooves in alinement with the grooves in said block, retaining blocks with bifurcated ends arranged between said rails and the blocks carried by said plates, bolts extending through the bars and into the bifurcated ends of said last named blocks, short rail sections between the adjacent portions of said plates with grooves in the tread surface thereof alining with the grooves in the plate block and cross braces extending between said short rails.
- 55 2. A railroad crossing comprising crossing plates, rail engaging bars carried thereby and defining crossed rail seats, an upstanding block at the intersection of the crossed seats and projecting slightly above said rail engaging bars with cross wheel flange grooves in the upper face thereof, rails having their ends received in said seats, flanges carried by the tread portions of said rails to define grooves in alinement with the grooves in said block, retaining blocks with the grooves in said block, retaining blocks with
- 60 65 with the grooves in said block, retaining

blocks with bifurcated ends arranged between said rails and the blocks carried by said plates, bolts extending through the bars and into the bifurcated ends of said last named blocks, short rail sections between the adjacent portions of said plates with grooves in the tread surface thereof alining with the grooves in the plate block, and interlocked cross braces extending between said short rails.

3. A railroad crossing comprising crossing plates, rail engaging bars carried thereby and defining crossed rail seats, an upstanding block at the intersection of the crossed seats and projecting slightly above said rail engaging bars with cross wheel flange grooves in the upper face thereof, rails having their ends received in said seats, flanges carried by the tread portions of said rails to define grooves in alinement with the grooves in said block, retaining blocks with bifurcated ends arranged between said rails and the blocks carried by said plates, bolts extending through the bars and into the bifurcated ends of said last named blocks, short rail sections between the adjacent portions of said plates with grooves in the tread surface thereof alining with the grooves in the plate block, interlocked cross braces having rail engaging portions at their opposite ends for engagement with said short rails and removable blocks associated with said braces adapted to be secured thereto and in contact with the short rails.

4. A railroad crossing comprising crossing plates, rail engaging bars carried thereby and defining crossed rail seats, an upstanding block at the intersection of the crossed seats and projecting slightly above said rail engaging bars with cross wheel flange grooves in the upper face thereof, rails having their ends received in said seats, flanges carried by the tread portions of said rails to define grooves in alinement with the grooves in said block, retaining blocks with bifurcated ends arranged between said rails and the blocks carried by said plates, bolts extending through the bars and into the bifurcated ends of said last named blocks, short rail sections between the adjacent portions of said plates with grooves in the tread surface thereof alining with the grooves in the plate block, cross braces having rail engaging flanges at the terminal ends thereof, flanges positioned inwardly of each end and having recesses in the upper faces thereof with a bolt receiving opening in the outer wall of said recess, a removable block associated with said inwardly positioned flanges and having openings therein registering with the aforesaid opening and locking bolts extending through said registering openings, the block adapted for engagement with the adjacent face of the short rail.

5. A railroad crossing comprising cross-

- ing plates, rail engaging bars carried thereby and defining crossed rail seats, an upstanding block at the intersection of the crossed seats and projecting slightly above 5 said rail engaging bars with cross wheel flange flange grooves in the upper face thereof, rails having their ends received in said seats, flanges carried by the tread portions of said rails to define grooves in alinement 10 with the grooves in said block, retaining blocks with bifurcated ends arranged between said rails and the blocks carried by said plates, bolts extending through the first named blocks in 15 the bifurcated ends of said last named blocks, short rail sections in the tread surface thereof alining with the grooves in the plate block, cross braces connected together at their contacting portions and in engagement with the short rails at their outer ends and removable blocks arranged to engage said short rails and be locked to said cross braces. 20 6. A railroad crossing comprising cross plates, rail engaging bars carried thereby and defining crossed rail seats, an upstand- 25
- ing block at the intersection of the crossed seats and projecting slightly above said rail engaging bars with cross wheel flange grooves in the upper face thereof, rails having their ends received in said seats, flanges carried by the tread portions of said rails to define grooves in alinement with the grooves in said block, retaining blocks with bifurcated ends arranged between said rails and the blocks carried by said plates, bolts extending through the first named blocks in the bifurcated ends of said last named blocks, short rail sections in the tread surface thereof alining with the grooves in the plate block, cross braces connected together at their contacting portions and in engagement with the short rails at their outer ends and removable blocks arranged to engage said short rails and be locked to said cross braces, said blocks and cross braces being provided with registering openings and sockets accommodating locking means associated therewith. 30 35 40 45

In testimony whereof I affix my signature.

JOSEPH GORINAC.
